TOY ANIMAL FIGURE

Thomas Dam, Aabybro, Denmark, assignor to Dam
Things Establishment, Vaduz, Liechtenstein

Filed Mar. 10, 1964, Ser. No. 78,937

Term of patent 14 years

(Cl. D34—2)

FIG. 1

FIG. 2

FIG. 5

FIG. 4

FIG. 6

FIG. 1 is a side view of the toy animal figure from the left showing my new design;

FIG. 2 is a side view of the same from the opposite side;

FIG. 3 is a front view of the toy animal figure of my new design;

FIG. 4 is a view of the doll from the front top, slightly inclined;

FIG. 5 is a perspective view seen from the front slightly downward; and

FIG. 6 is a rear view of the toy animal figure.

I claim:

The ornamental design for a toy animal figure, as shown.
